MACHINE GUN

Clarence E. Simpson, Springfield, Mass.

Application April 20, 1934, Serial No. 721,564

2 Claims. (Cl. 42—75)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a machine gun.

In a machine gun, head-space is the distance between the front face of the breech bolt and the cartridge seating cone of the chamber of the gun barrel when these parts are in battery.

10 If the head-space is incorrect the gun will fail to function or it will function unsatisfactorily, causing stoppages and damaging the parts.

In guns of the Browning type the barrel is 15 threadedly secured to the barrel extension and maintained in position relative thereto by a locking spring carried by the barrel extension and selectively engageable in any one of a series of notches on the barrel. The correct head space adjustment must be established by trial and this 20 involves the tasks of assembling, disassembling, adjusting and then reassembling the gun.

With a view to permitting a more convenient and more rapid adjustment for head-space the present invention resides in the provision of an 25 externally accessible latch for holding the barrel in position of adjustment.

With the foregoing and other objects in view, the invention resides in the novel arrangement and combination of parts and in the details of 30 construction hereinafter described and claimed, it being understood that changes in the precise embodiment of the invention herein disclosed may be made within the scope of what is claimed without departing from the spirit of the invention.

35 A practical embodiment of the invention is illustrated in the accompanying drawing, wherein:

Fig. 1 is a view partly in side elevation and partly in longitudinal section of a machine gun showing only the receiver, barrel and barrel 40 mounting.

Fig. 2 is an enlarged longitudinal sectional view of the barrel lock.

Fig. 3 is a sectional view on the line 3—3 of 45 Fig. 2.

Fig. 4 is a sectional view showing the plunger disengaged from the barrel.

Fig. 5 is a sectional view on the line 5—5 of 50 Fig. 3.

Fig. 6 is a view in elevation of the plunger.

Referring to the drawing by characters of reference, there is shown a portion of a machine gun of the Browning air-cooled type, including a breech casing 4, a trunnion block 5 in the forward 55 end of the casing, a breech bolt 6 in the casing,

a barrel 7 slidably mounted in the trunnion block and having a threaded connection 8 with a barrel extension 9 housed in the breech casing. An apertured jacket 10 which may be of any desired length, surrounds the barrel and is held in spaced relation with respect thereto by virtue of its mounting which consists of a threaded connection 11 on the trunnion block and a ring 12 fitting on the barrel and preferably carried by the jacket.

A portion of the barrel forward of the trunnion block is provided on its exterior surface with a plurality of longitudinally extending grooves 13—13 adapted to selectively receive the tongue 14 of a latch 15.

The latch is in the form of a plunger and is mounted in a cylinder 16 fixed to the jacket 10 and projecting on the inside and the outside thereof. The outer end of the plunger is formed with a head 17 whereby it may be grasped and withdrawn from engagement with the gun barrel.

A helical spring 18, normally urging the plunger towards the gun barrel, is confined between the closed inner end 19 of the plunger and a 25 plug 20 which is disposed in the plunger and which is fixed to the cylinder 16 by a pin 21. The pin 21 passes through bayonet slots 22—22 in the opposite walls of the plunger. When the plunger is depressed with its tongue 14 in one 30 of the grooves 13 of the gun barrel Fig. 2, the pin 21 is at the outer or upper end of each slot 22 (Fig. 2). When the plunger is withdrawn from engagement with the barrel against the action of the spring 18 (Fig. 4), it may be rotated 35 to place the pin in the inner offset portion of the bayonet slots, in which case the plunger is held in withdrawn position.

By virtue of this arrangement adjustment for 40 head-space may be readily made without disassembling the gun. The operation consists merely in withdrawing the plunger, rotating the barrel to advance or retract it relative to the barrel extension, determining the proper head-space by trial of the gun mechanism and then releasing 45 the plunger.

I claim:

1. In a machine gun, a breech casing, a member within the casing, a barrel having one end 50 slidably mounted in the breech casing and threadedly connected to said member, the outer portion of said barrel having an annularly arranged series of longitudinally extending grooves, a jacket surrounding the barrel and attached to the barrel casing, a cylinder fixed in the jacket, 55

a plunger in the cylinder, said plunger having oppositely arranged bayonet slots, a plug within the plunger, a pin fixing the plug to the cylinder and passing through the bayonet slots of the plunger, and a spring confined between the plug and the plunger and normally holding the plunger in engagement with one of the grooves of the barrel.

2. In a machine gun, a breech casing, a member within the casing, a barrel having one end

slidably mounted in the breech casing and threadedly connected to said member, the outer portion of said barrel having an annularly arranged series of longitudinally extending grooves, a jacket surrounding the barrel and attached to the barrel casing, and a latch carried by the jacket and selectively engageable in the grooves of the barrel upon rotational displacement of the barrel.

CLARENCE E. SIMPSON. 10
